UNITED STATES PATENT OFFICE.

JOSEPH KOMOROUS, OF RIVERSIDE, ILLINOIS, ASSIGNOR TO PARISIAN NOVELTY CO., OF CHICAGO, ILLINOIS.

TIME INDICATOR.

Application filed November 1, 1924. Serial No. 747,302.

To all whom it may concern:

Be it known that I, JOSEPH KOMOROUS, a citizen of the United States, and a resident of Riverside, county of Cook, and State of Illinois, have invented, certain new and useful Improvements in Time Indicators, of which the following is a specification.

My invention relates to improvements in time indicators, especially adapted for use in fixing for ready reference the time consumed or to be consumed in the performance of a task or in carrying out an operation, the main object of the invention being to provide a simple device of this character capable of economical manufacture and highly efficient in use.

Other objects will appear hereinafter.

The invention consists in the combinations and arrangements of parts hereinafter described and claimed.

The invention will be best understood by reference to the accompanying drawings forming a part of this specification, and in which,

Fig. 1 is a front elevational view of my improved time indicator;

Fig. 2 is a vertical section taken on the line 2—2 of Fig. 1; and

Fig. 3 is an enlarged fragmental view, illustrating in particular a securing lug struck from the backing plate.

In the preferred form of construction as illustrated in the accompanying drawing it will be seen that my improved time indicator includes a circular dial plate 4 formed with a rearwardly curved marginal edge region 5 which is bent over upon itself at 6 and crimped upon the concaved periphery 7 of the backing plate 8 which is made in the dish-shaped form shown (Fig. 2), there being a circular re-enforcing plate 9 having snug fit upon the rear face of the dial plate with its rearwardly curved circumferential region 10 bound between the dial plate and a shoulder 11 formed upon the circumference of the backing plate 8. As illustrated in Fig. 2, the central portion of the re-enforcing plate 9 is held tightly between the central flat portions of the dial plate 4 and backing plate 8, respectively. From the

backing plate 8, at diametrically opposite positions, are struck out the lug elements 12 which are bent radially outward beyond the periphery of the backing plate and rearwardly offset therefrom so as to serve as means by which to support the time indicator from a panel board as 13 or any convenient wall structure, it being observed that each of the lugs 12 is provided with an aperture 14 adapted to receive a screw element 15 or other suitable means for attachment to the panel board or wall.

Centrally piercing the backing plate, re-enforcing plate and dial plate is a pivot stud 16 which projects outwardly from the dial plate for the purpose of operatively supporting the parts now to be described, it being observed that the opposite ends of the pivot stud are formed with the flanges 17 and 17'. Upon the face of the dial plate within the compass of the circumferential region 5 thereof is printed or otherwise produced the time characters 18 consisting of the usual time-piece ordinals from one to twelve arranged precisely as on the face of a watch or clock. Projecting radially outward from each ordinal upon the circumferential region 5 is an hour marking 19. Between the hour markings 19 are subdivisional markings 20 each representing a period of five minutes. Upon the face of the dial within the compass of the hour ordinals are provided subject headings or markings as 21, which relates to the matter or service or operation, as the case may be, in connection with which the time indicator is to be employed. In the present instance I have shown but two subject markings consisting of the words "Suds 1" and "Suds 2," which relate to operations in a laundry; but it will be obvious that a great number of subject headings may thus be provided upon the dial between the circle of ordinals and the pivot stud. It will also be understood that while I have here shown subject headings characteristic of operations in a laundry, the subject headings may consist of any matter characteristic of the duties or operations in connection with which the indicator is to be employed.

2

Mounted for movement upon the pivot stud 16 in front of the dial plate is a subject designator 22, herein shown as colored for yellow, and also herein shown as projecting a distance beyond the dial plate. Also movably mounted upon the pivot stud 16 in front of the subject designator is a transparent disc 23 consisting preferably of celluloid, this transparent disc being of a dimension to encompass the hour numerals, as clearly shown in Fig. 1. On this transparent disc 23 is painted or otherwise produced a time set index 24, designed upon the movement of the transparent disc to register with or point out the time markings, hereinbefore described, on the dial plate. In the present instance this time set index, is produced in imitation of red. Further mounted for movement upon the pivot stud 16 is a time stop index 25 designed also to register with or point out the time markings on the dial plate. In the present instance this time stop index is lined for indications of black. This time stop index corresponds as to its purpose with the minute hand of a watch or clock since its position in relation to the ordinals in a clock-wise direction designates the period of time after the hour. The subject designator, the transparent disc with its time set index and the time stop index are bound together in frictional contact against the dial plate by means of the pivot stud 16, it of course being understood that one of the flanges on the pivot stud will not, in assembling, be crimped into retaining position until the parts have been properly mounted. The subject designator, transparent dial with its time set index and the time stop index are so bound together upon the pivot stud that while each of them is freely manually movable with respect to the other, yet each one will be held by friction in any position to which it is moved about the face of the dial plate.

By way of illustrating the operation of the time indicator, let us assume that it is to be employed in connection with operations in a laundry, for instance to show the predetermined period of time that a batch of clothes is to be washed in "Suds 2." Let us assume further that the time the washing operation is to commence is forty minutes past eleven; and that the washing operation is to continue for a period of twenty-five minutes. To register these facts, the subject designator is moved on its pivot to occupy a position over "Suds 2" and the time set index is moved to indicate the sub-divisional line 20 which denotes forty minutes past eleven, as shown in Fig. 1. Since each sub-divisional line 20 denotes a five minute period of time, and since there remains four sub-divisional periods between the position of the time set index at forty minutes past eleven and the ordinal twelve, twenty

minutes of the period are thus accounted for, so that the time stop index 25 is placed opposite the ordinal one which signifies that the washing operation in "Suds 2" will be completed at five minutes after twelve. Having thus set the time indicator, it is only necessary to observe the time on a watch or clock from which will be determined when the watch or clock is five minutes past twelve that the washing operation in "Suds 2" is completed. In this manner my improved time indicator will show for reference the subject matter or operation to which attention is being given, the time on which the task or operation commences and the time on which the task or operation is to be completed.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A time indicator including a dial plate; a backing plate therefor, said dial plate and backing plate having curved marginal regions; a re-enforcing member combined with the backing plate to provide an annular groove in which the marginal edge of the dial plate is crimped; a member connecting the dial plate, backing plate and re-enforcing member, and means on said member for co-operating with the dial plate, substantially as described. 95 100 105

2. A time indicator comprising a dial plate having time and subject markings thereon; a backing plate and re-enforcing plate with which said dial plate is united, said re-enforcing plate having means for attachment to an object; a central pivot stud projecting from the dial plate, backing plate and re-enforcing member; a time set index and a time stop index adapted to register with the time markings on the dial plate; a subject designator adapted to register with the subject markings on the dial plate; said time set index, time stop index and subject designator being mounted in frictional engagement on said pivot stud and adapted for independent manual movement thereon, substantially as described. 110 115 120

3. A time indicator comprising a dial plate and a backing plate secured together, said dial plate having time and subject markings thereon, said backing plate having means thereon for attachment to an object; a central pivot stud projecting from the dial plate; a subject designator movably 125 130

mounted on said pivot stud; a transparent disc movably mounted on said pivot stud and having a time set index thereon; a time stop index movably mounted on said pivot stud, said subject designator, time set index and time stop index being differently characterized; said subject designator, trans-

parent disc and time stop index being frictionally held together on the pivot stud and adapted each to be held in the position whereat it is set, substantially as described.

In testimony whereof I have signed my name to this specification.

JOSEPH KOMOROUS.
